UNITED STATES PATENT OFFICE.

BENJAMIN CHARLES CARTER, OF LONDON, ENGLAND.

CENTRIFUGAL SEPARATOR.

Application filed October 23, 1926, Serial No. 143,725, and in Great Britain March 14, 1925.

This invention relates to centrifugal separators and consists in improved constructions of separator especially suitable for insertion in the oil circulating system of 5 internal combustion engines for freeing the lubricating oil from fine solid matter; or for freeing fuel oil or other liquids from air or solid impurities; or for freeing air from solid and liquid impurities; and also 10 applicable to other purposes.

The separators of the invention designed for cleaning liquids comprise a bowl filled with the liquid to be cleaned and rotating with it at a high speed, longitudinal vanes 15 ensuring that the liquid adjacent to the bowl shall be at rest relatively to it, while fluid further removed from the surface of the bowl can flow slowly but freely along a path parallel with the axis of rotation and 20 divided from the remainder of the bowl by a perforated wall or equivalent means which will permit the outward movement of solid particles of impurity under centrifugal action but will tend to prevent the aggregate 25 or conglomerated deposit of impurity which collects within the bowl from returning into and choking the axial path. The bowl and the perforated wall or equivalent dividing 30 means are surfaces of revolution, conveniently right circular cylinders or barrel-shaped, and their axis is the axis of revolution. The liquid to be cleaned may itself 35 be caused to rotate the bowl and perforated cylinder; for this purpose the liquid may be propelled into the separator through a helical passage of decreasing pitch formed in the stationary inlet; in its axial flow within 40 the separator it may be guided parallel to the axis by longitudinal vanes in the perforated cylinder; and it may leave the separator through another helical path of decreasing pitch and opposite twist formed 45 in the rotating outlet. The effectiveness of the separator may be increased by dividing the space between the bowl and the perforated cylinder by transverse partitions or 50 vanes. Where the liquid contains impurities lighter than itself there may be a perforated cylinder bounding the axial liquid path on its inner surface; and if the lighter impurities are gaseous, as in the case of oil 55 containing air, a relief valve may be provided to permit the escape of the gases from within this inner perforated wall.

In separators designed for cleaning air an 55 imperforate bowl is not essential. The air is led through a perforated cylinder the central part of which is filled by a stream lined body, which may consist of a rotating portion carrying the cylinder by radial 60 vanes and a stationary portion containing the bearings of the rotating part. Such a separator may be driven, as above described, by the air to be cleaned being pumped through it along suitable helical paths, or it 65 may be fitted with vanes which will cause its rotation when it is carried through the air at a high speed, as, for instance, upon an aeroplane.

Various embodiments of the invention are 70 illustrated diagrammatically and by way of example in the accompanying drawings, in which:—

Fig. 1 is a vertical section of a centrifugal separator for separating foreign particles 75 from oil or other liquid;

Fig. 2 is a section on the plane 2—2 in Fig. 1;

Fig. 3 is a vertical section of part of a centrifugal separator through which the 80 liquid passes several times lengthwise to and fro;

Fig. 4 is a vertical section of part of a centrifugal separator through which the 85 liquid passes in several parallel streams;

Fig. 5 is a vertical section of part of a centrifugal separator for treating liquid containing air;

Figs. 6 and 7 are longitudinal and transverse sections of a centrifugal separator for 90 separating dust and sand from air;

Figs. 8 and 9 are similar views of another form of centrifugal separator for separating dust and sand from air; and

Fig. 10 is a longitudinal section of a form 95 of separator which is arranged vertically and in which certain parts are made barrel-shaped.

In the centrifugal separator shown in Figs. 1 and 2, an annular drum is formed 100 with a perforate inner wall 1, an imperforate outer wall or bowl 2, and imperforate annular ends 3, 4 connecting said walls. The drum is mounted in antifriction or other suitable bearings 5, 6 so as to offer 105 little frictional resistance to rotation. A running gland 7 on the inlet end of the drum receives a stationary hollow inlet boss

8 which communicates with the oil supply. The running gland may be formed with a helical groove 9, of opposite twist to the direction of rotation to aid in preserving a 5 fluid tight running fit between the gland and the inlet boss 8. The drum communicates with the inlet boss 8 through the inlet end 10 of the inner wall 1, and with a receiving reservoir or communication (not 10 shown) through the outlet end 11 of the inner wall 1. The drum may be mounted in a stationary casing 12 of which the inlet boss 8 may form part.

The inlet boss 8 is fitted internally with 15 one or more helical vanes 13 decreasing in pitch towards the rotary inlet end 10, and forming a helical passage or passages of decreasing pitch and radial width between a central stationary cone 14 and the wall of the 20 inlet boss 8. These helical paths terminate adjacent to the rotary inlet end 10 in jets of small cross sectional area. Within the inner wall 1 is a central rod or tube 15 of the same diameter as the base of the cone 25 14. The annular space 16 between this rod or tube and the inner wall of the drum forms a direct oil passage-way through the drum, and is divided by approximately straight radial vanes 17 extending from end 30 to end. Upon these radial vanes are delivered the streams of oil issuing from the jets and adjacent the inlet end 10.

The outlet end 11 of the divided annular space 16 communicates with the flared rotating outlet boss 18, which has one or more internal helical vanes 19, decreasing in pitch towards the outer end and twisting in the opposite direction to the helical vanes 13 in the stationary inlet boss 8. These direct the 40 oil in the reverse direction to that of the rotation of the drum and convert into velocity the remaining pressure to which the oil is subjected during rotation of the drum. The oil issues as jets which by their reaction 45 assist in causing the drum to rotate. The drum is thus driven in the manner of the rotor of a reaction turbine.

The straight radial vanes 17 may be curved at each end so that the oil is transferred to and from them with minimum shock and loss of energy.

Within the bowl 2 are radial vanes 20 dividing it into sectors, and compelling the oil to rotate with the bowl. If desired transverse vanes 21 may be fitted in the bowl 55 dividing the annular quiescent space between walls 1 and 2 into separating zones.

Oil is delivered under pressure to the stationary inlet boss 8, and the stationary helical vanes 13 in this boss cause the pressure 60 of the oil to be partially converted into velocity at the exit jets of these vanes. The oil completely fills the annular space 16 and the bowl 2, and during its passage 65 through the separator the oil travelling ax-

ially along the annular space is divided from the oil in the bowl by the perforate inner wall 1. The oil in the bowl is thus practically motionless relative to the bowl. The axial velocity of the oil along the divided annular space 16 is small, and the tendency for turbulence to prevent separation of particles is thus kept low, whereas the circumferential velocity is high enough to produce great centrifugal effects. Thus 70 the oil is constrained to pass slowly through the apparatus in a rapidly rotating divided cylindrical sheet, and the particles of dirt have but a short distance to move radially in order to traverse the perforate inner wall 80 1 and become separated from the axially moving oil stream. The particles are then subjected to an increasing centrifugal action tending to deposit them on the outer imperforate wall 2 of the drum. 85

In order to make the radial velocity of the particles as high as possible, the product of the square of the angular velocity and the radius at which separation is effected is made as great as possible, and the viscosity 90 of the liquid is made as small as possible. The angular velocity of the drum is made high by making its efficiency as a turbine as high as possible and by diminishing the viscosity of the liquid. The viscosity of the 95 liquid is made small by working at as high an oil temperature as possible.

The circumferential velocity of the drum at the region of entry 10 of the oil requires 100 to be of the same order as the jet velocity from the stationary entry vanes 13. The latter is limited by the pressure drop available, the viscosity of the oil, and the minimum jet area it is practicable to adopt. The radius of the stationary inlet vanes is 105 therefore made small to obtain high rates of rotation.

In the arrangement described the important centrifugal action takes place in the divided annular space 16 and the radius at 110 which a particle is separated is equal to the radius of the stationary inlet vanes. A greater centrifugal effect may be obtained by leading the oil out to a larger radius during a part of its travel through the apparatus, as by making the inner perforate wall 1' and tube 15' barrel-shaped (Fig. 10), the bowl 2' and casing 12' being made spherical in that event; for the same thickness of annular space, the axial velocity in the part of greater diameter would be less and the time of traversing the apparatus greater, both of which factors tend to give improved separation. The annular space should be made as thin as possible, and the drum long and of small diameter (rather than short and of large diameter) so that the distance the particles have to pass radially to effect separation is small, and the time of traversing the apparatus is large. 115 120 125 130

Short tubular outward projections, indicated at 1² in Fig. 10, may be arranged at the holes in the perforate wall to prevent return flow from the annular bowl back into the annular space within the inner wall with accompanying return of particles; or, if preferred, the holes in the perforate inner wall may be counter-sunk from either the outside or the inside, as indicated at 1³, or both expedients may be adopted.

The retention of the particles within the annular drum involves some degree of adhesion to the walls and caking of the deposit. It may be advantageous and desirable to give the walls a rough surface or to coat them with grease or other suitable substance to facilitate retention, but with engine oil the natural gumminess of the deposit may suffice. Cooling of the outside of the drum facilitates gumming and retention of deposit. For this purpose the drum may be provided with cooling fins 1⁴ (Fig. 10), which may be exposed to the atmosphere or other cooling medium. The inner perforate wall tends to check or prevent any flakes or deposit which may become detached from the wall of the bowl from re-entering the path along which the oil flows axially, as might otherwise happen when the apparatus is stopped or is being started, and so obstructing the flow of the oil.

For some purposes, for instance for separating water as well as solid impurities from gasoline, the device may be set with its axis vertical (Fig. 10) and the lowermost perforations in the wall 1' may be omitted. By this means the lower end of the annular space between the walls 1' and 2' is wholly cut off from the through-flowing stream, and permits the undisturbed accumulation of any water that may be separated from the gasoline.

Increased separation may be attained by passing the oil in parallel (Fig. 3) or in series (Fig. 4) axially through a system or nest of concentric or symmetrical annular spaces 160 in a separator having inner perforate walls 100 and outer imperforate walls 200, corresponding to the inner perforate wall 1 and the outer imperforate wall 2 in Fig. 1. In this arrangement alternate imperforate and perforate walls are arranged between the innermost and outermost walls of the drum, and the separated matter accumulates on the series of imperforate walls or cylinders. This arrangement is directed mainly to extracting matter quickly. The arrows in Figs. 3 and 4 indicate the direction of flow of the oil from the inlet end 10 of the divided annular space 160 to the outlet end 11 thereof.

The oil may be forwarded through the separator by either a pressure or a suction pump of any convenient type.

It will be understood that the ends of the drum and the casing may be detachable, as is shown for the inlet end of the drum and casing in Fig. 1, to facilitate access thereto for cleaning out the separated matter.

In treating oil containing air, the air tends to keep near the axis of rotation under the centrifugal action, and, as shown in Fig. 5 a separate outlet 22 may be provided through which the air reaches a small relief valve 23 loaded to a suitable pressure and located in the central tube 15 forming the inner wall of the annular space 16. The relief valve casing runs in a stationary gland 24, which can communicate with the atmosphere through a cock 25.

The separator as described may be constructed small in size and light in weight, and has the important feature that no mechanical high speed drive or slipping clutch is involved.

Such a separator may be incorporated in the sump of an aircraft or other internal combustion engine, which may be provided with two scavenging pumps, one at each end, each pump being more than capable of dealing with the oil in circulation. Oil is pumped by the rear pump through the separator to the well of the forward pump and thence back to the oil tank. A by-pass valve may be provided for short-circuiting the separator when the oil pressure exceeds a predetermined limit.

Alternatively, the separator may be arranged between a pressure feed pump outlet and the parts to be lubricated.

When the drum outlet communicates with a pipe line or reservoir, a running gland may be provided for effecting the communication, and fixed vanes may be used in the pipe line or reservoir.

In the form of construction of centrifugal separator shown in Figs. 6 and 7, the bowl is formed with a perforate inner wall 101 and an outer wall 201 which may be imperforate or perforate as indicated at 37. The bowl is mounted on a central spindle 26, supported in antifriction bearings 27, 28 in an inner housing 29, which is located by means of radial webs or vanes 30 within an outer housing 31. The outer housing 31 is adapted to be applied to the air intake 32 to an internal combustion engine. Helical vanes 33 mounted within the entry of the bowl cause the air drawn in by the engine to rotate the bowl in flowing therethrough. Radial vanes 34 mounted within the perforate inner wall 101 and which may be continuous with the vanes 33, divide the annular space 161 between the inner peripheral wall and the central body part 150 into longitudinal air passage-ways. Curved vanes 35 which may be continuous with the vanes 34 may be located within

the outlet end of the bowl for straightening out the air stream before it passes into the air intake to the engine to prevent turbulence of the air in the intake. The vanes 5 30 may be curved for the same purpose. The central body 150 increases the mean radius of airflow and has a streamline formation.

In addition to or in lieu of using helical 10 vanes within the bowl for imparting a rotational effect to it, the bowl may be furnished with exterior helical vanes 36 or the like, which are adapted to cause rotation of the bowl by the slip stream or relative air flow, 15 when the separator is used in an exposed position on an aircraft or other moving vehicle.

In the form shown in Figs. 8 and 9, instead of the spindle 26 being secured to the bowl and rotating in bearings in a stationary 20 housing 29 as in Fig. 6, it is secured in the stationary housing 29, and the bowl rotates in bearings 38, 39, on the spindle.

Further, instead of the plain perforate inner wall 101 as in Fig. 6, a series of annular 25 partitions 102 may be employed, and the outer wall may be pocketed and perforated as at 202. The inner edges of the annular partitions 102 together with those of the radial vanes 30 form in effect a perforate 30 inner wall.

A collector 40, in the form of a casing with a radial or outer outlet 41 may be attached to the other stationary housing and extend over part of the bowl including the 35 perforate area. This casing serves to gather the dust or sand which has been separated from the air.

When the separator is to be used for separating air or other impurity lighter than 40 the liquid being treated, the wall 1 may be made the imperforate wall and the wall 15 may be made the perforate wall, in which case the wall 2 is dispensed with.

What I claim is:

45. 1. A centrifugal separator comprising a bowl rotatable at high speed upon its axis, longitudinal vanes upon the inner surface of the wall of said bowl, an inlet and an outlet to said bowl at opposite ends thereof, and 50 means continuously dividing the fluid path between said inlet and outlet from the remainder of the bowl throughout the entire length of the bowl said means permitting passage of fluid and fine impurities along 55 such path while checking return of conglomerated solid matter to said path.

2. A centrifugal separator comprising a bowl rotatable at high speed upon its axis, longitudinal vanes upon the inner surface 60 of the wall of said bowl, an inlet and an outlet to said bowl at opposite ends thereof, and a continuous perforated wall dividing the fluid path between said inlet and outlet from the remainder of the bowl throughout 65 the entire length of the bowl; said wall per-

mitting passage of fluid and fine impurities along such path while checking return of conglomerated solid matter to said path.

3. A centrifugal separator comprising a rotatable bowl, inlet and outlet means admitting fluid to pass axially through said bowl, and vanes in the path of said fluid adapted to deflect the same and thereby cause rotation of said bowl.

4. A centrifugal separator comprising a 75 rotatable bowl, a fixed inlet in line with the axis of said bowl, helical vanes in said inlet adapted to impart a whirling motion to fluid passing axially therethrough and eject it in the form of jets from said inlet, and 80 vanes in said bowl against which such jets impinge, thereby to cause rotation of the bowl.

5. A centrifugal separator comprising a 85 rotatable bowl, a fixed inlet in line with the axis of said bowl, helical vanes in said inlet adapted to impart a whirling motion to fluid passing axially therethrough and eject it in the form of jets from said inlet, vanes in said bowl against which such jets impinge 90 so as to cause rotation of the bowl, an axial outlet rotating with said bowl, and helical vanes in said outlet extending in the opposite direction from the first-named vanes to convert the whirling motion of the fluid in 95 said bowl into a straight axial flow.

6. A centrifugal separator comprising a rotatable bowl, longitudinal vanes within said bowl, a wall within the bowl having the form of a surface of revolution about the 100 axis of rotation and being perforated from one end substantially to the other, means admitting liquid to pass axially through the interior of said perforated wall from end to end thereof and to fill the bowl through the 105 perforations, and means disposed axially of said separator for permitting the escape of gases.

7. A centrifugal separator, comprising a 110 rotary bowl having an inlet at one end and an outlet at the other and embodying connected outer and inner, substantially-cylindrical members disposed in coaxial relation, the inner member being perforated from its inlet end approximately to its outlet end; 115 and means for admitting fluid at the inlet end of said inner member to travel axially through the interior thereof to the outlet end, whereby matter to be separated contained in the traveling fluid will be caused 120 to pass radially outward through the perforations as the axial movement of the fluid continues.

8. A centrifugal separator, comprising a 125 rotary bowl embodying connected outer and inner, substantially-cylindrical members disposed in coaxial relation, the inner member being perforated from one end approximately to the other; a stationary cylindrical member extending axially through said in- 130

ner cylindrical member and providing an radially outward through the perforations open-ended annular passage therebetween; as the axial movement of the fluid con-
and means for admitting fluid at the inlet tinues. 10
end of such passage to flow axially there-
5 through to the outlet end of the passage, In testimony whereof I have signed my
whereby matter to be separated contained in
the traveling fluid will be caused to pass name to this specification.

BENJAMIN CHARLES CARTER.
